UNITED STATES PATENT OFFICE.

HARRY S. HART, OF CHICAGO, ILLINOIS, ASSIGNOR TO NATIONAL DUMP CAR COMPANY, OF CHICAGO, ILLINOIS, A CORPORATION OF MAINE.

DOOR-OPERATING MECHANISM.

1,380,377.

Specification of Letters Patent.

Patented June 7, 1921.

Application filed September 26, 1919. Serial No. 326,555.

To all whom it may concern:

Be it known that I, HARRY S. HART, a citizen of the United States, residing at Chicago, in the county of Cook and State of Illinois, have invented certain new and useful Improvements in Door-Operating Mechanism, of which the following is a specification.

This invention relates to door operating mechanism for railway cars.

The object of my invention is to simplify and improve door operating mechanism for railway cars, whereby the movement of the doors may be controlled efficiently, and whereby the doors when supported in closed position will be retained positively and prevented from sagging to overcome leakage.

This and other objects are accomplished by means of the arrangement disclosed on the accompanying sheets of drawings, in which:—

Figure 1 is a fragmentary side elevation of a railway car embodying my invention;

Fig. 2 is a transverse sectional view of the same car, showing the doors in open and closed positions;

Fig. 3 is a fragmentary enlarged sectional view of my door operating mechanism; and

Fig. 4 is a fragmentary enlarged side elevation of the same.

The various novel features of my invention will be apparent from the following description and drawings, and will be particularly pointed out in the appended claims.

Referring to the figures of the drawings, it will be noted that I have shown a general service railway car, having sides 10, ends 11 and a floor which, in this instance, includes a plurality of side dump doors 12, which preferably are pivoted at 13 along their inner edges to the center sill construction 14. These doors when closed occupy a horizontal position and preferably extend the full length of the car, there being any desired number of floor doors on each side of the car.

Referring to Fig. 2, it will be noted that the left hand floor door 12 is in its raised or closed position, and that the right hand door is in its open position for side dumping purposes, and in such position is supported by a stop member 15.

This invention has to do primarily with door operating mechanism. This mechanism includes a shaft 16, preferably having

hexagonal or squared portions, there preferably being an operating shaft in each quarter of the car. Affixed to the hexagonal or squared portions of each of the shafts 16 are a plurality of arms 17, which preferably extend at right angles with respect to the shaft 16, and are spaced along the latter.

As shown in Figs. 1, 3, and 4, and at the left hand side of Fig. 2, the door 12 is in closed position and is held or supported in said closed position by the arms 17, which in this position extend vertically and press upwardly against the doors 12 near their outer edges. Preferably there are two arms 17 under each door, one at each end thereof. The shaft 16, when coöperating with the arms 17 to retain the doors 12 in closed position, occupies the lower inner end of a plurality of arcuate slots 18 which are formed in the cross beams 19. These slots 18 extend downwardly and inwardly from the sides of the car and from a point substantially on a horizontal line from the doors when in closed position to a point considerably below and under the doors in the same position. The shaft, in each case, therefore, moves downwardly and inwardly to reach its supporting position, and upwardly and outwardly in moving to its non-supporting position.

Adjacent each of the arcuate slots 18 is a rack member 20, which is secured to the car frame structure, said racks meshing with gears 21 fixed to the shafts 16. These racks are adjacent the associated shaft and also extend downwardly and inwardly to conform with the shaft movements. To permit the doors 12 to drop into an open position for dumping purposes, the shafts 16 on the left hand side of the car will be rotated in a clockwise direction, and the shafts 16 on the right hand side of the car will be rotated in a counter-clockwise direction. As the shafts are thus rotated, the arms 17 gradually move out of a supporting position with respect to the doors, and the shafts 16 move laterally outward from a position under the doors to a position beyond the outer edge of the doors, whereupon the latter are free to move into a full open position.

During this opening movement, it will be understood that the doors are lowered gradually as the arms swing from a supporting toward a non-supporting position. The doors are shown in an open position at the

right hand side of Fig. 2, the shafts 16 being shown in the outer end of the arcuate slot 18, and the arms 17 extending vertically downward.

5 The doors may be closed in any desired succession, being independent of each other. Said doors are raised directly and individually into closed position in a manner fully disclosed in my co-pending application Serial No. 278,408, filed February 21, 1919, now Patent No. 1,318,444, issued October 14, 1919. The means for thus closing each of the doors includes a handle 22 having a slot 23 for slidably receiving a pin 24 fixed in a bracket 10 15 secured to the under side of the door. When the door is completely lifted by the handle 22 into closed position, the outer end of the handle may be moved laterally to overlie a supporting portion 26 of a bracket 27 whereby the door temporarily is 20 25 locked in closed position. It will be understood that the connection between the bracket 25 and handle 22 is made very loose to permit sidewise and lengthwise movement of the latter. It is understood also that the shaft 16 with its arms 17 form the final locking means for the doors, the handles 22 being moved away from the bracket portion 26 or temporary locking position by 30 35 the shaft in each case engaging projections 28 on the handles, the handles 22 being guided in their movements by a handle bracket 29 and an associated cam 30 on each handle as clearly set forth in my said patent. Accordingly when the shafts 16 are moved into a non-supporting position, the doors are all free to move into an open position.

If the doors are not completely raised by 40 the handles 22, the final closing movement may be made by the arms 17 which act in a cam-like manner lifting upwardly. By providing a plurality of these arms 17 for engaging a single door, the door in each 45 case is prevented from sagging or bulging, which would cause leakage. It will be noted that the arms 17, which engage the doors adjacent the side edges thereof, permit the location of the supporting shaft at a point 50 considerably below the doors when the shaft is in supporting position. By reason of this fact and because of the location of these arms on the shaft at points adjacent the door edges, the doors will be engaged by the 55 arms and held closed even if the door is bulged downwardly in the center, or if the door is bent down at one corner, the opposite corner will still be engaged by one of the arms, so that the door will be held in 60 closed position. The shafts 16 may be op-

erated by any suitable mechanism well known in the art.

It is my intention to cover all modifications of the invention falling within the spirit and scope of the following claims. 65

I claim:

1. In a general service car having a plurality of doors, means for directly lifting said doors to closed position individually, and a shaft carrying projecting means for 70 engaging said doors for holding the latter in closed position.

2. In a general service car having a plurality of doors, means for directly lifting said doors into a given position individually, 75 and a shaft carrying projecting means for engaging said doors for holding the latter in said given position.

3. In a general service car having a plurality of doors, means for directly moving 80 said doors into a given position individually, a shaft, and means carried by said shaft for engaging said doors for holding the latter in said given position.

4. In a general service car having a plurality of doors, means for directly moving 85 said doors into a given position individually, a shaft movable under the doors and movable from under the doors, means for guiding the movement of said shaft, and 90 means mounted on said shaft for engaging said doors when the shaft is in a position to support said doors through the means mounted thereon.

5. In a general service car having a door, 95 means for directly lifting said door to a closed position, a movably mounted shaft, and arms carried by said shaft which swing upwardly for engaging opposite ends of the door for supporting the latter in closed position. 100

6. In a general service car, the combination of a door hung for up and down swinging movement, a shaft movable downwardly and inwardly to reach a supporting position under said door in a given position, and an arm mounted on said shaft and swung upwardly to engage and support said door. 105

7. In a general service car, the combination of a movably mounted door, a shaft 110 movable downwardly and inwardly and under said door into a supporting position; said shaft being movable upwardly and outwardly into a non-supporting position, and projecting means on said shaft movable into 115 an upright position to engage and support said door.

Signed at Chicago, Illinois, this 22 day of September, 1919.

HARRY S. HART.
